(57) **CLAIM**

The ornamental design for a portion of a compound leverage hand tool, as shown and described.

DESCRIPTION

FIG. 1 is a front perspective view of a portion of a compound leverage hand tool showing my new design;

FIG. 2 is a front view thereof;

FIG. 3 is a back view thereof;

FIG. 4 is a top view thereof;

FIG. 5 is a left side elevation view thereof;

FIG. 6 is a right side elevation view thereof;

FIG. 7 is a bottom view thereof;

FIG. 8 is a front view of a portion of a compound leverage hand tool showing my new design with a different tool head shown in broken lines that forms no part of the claimed design or of a specified embodiment thereof;

FIG. 9 is a front perspective view of a portion of a compound leverage hand tool showing my new design with yet another different tool head shown in broken lines that forms no part of the claimed design or of a specified embodiment thereof;

FIG. 10 is a front perspective view of a portion of a compound leverage hand tool showing my new design with a further different tool head shown in broken lines that forms no part of the claimed design or of a specified embodiment thereof; and,

FIG. 11 is a back view of a portion of a compound leverage hand tool showing my new design with a still further different tool head shown in broken lines that forms no part of the claimed design or of a specified embodiment thereof.

The portion of a compound leverage hand tool that is the subject hereof may have a variety of tool heads attached to the position. The broken lines in the drawings show tool heads which are unclaimed subject matter that forms no part of the claimed design or of a specific embodiment. The portions of the article shown in broken lines form no part of the claimed design.
